(57) **CLAIM**

The ornamental design for a tissue box, as shown and described.

DESCRIPTION

FIG. 1 is a first side view of an embodiment of a tissue box; FIG. 2 is a top view of the tissue box shown in FIG. 1; FIG. 3 is a second side view of the tissue box shown in FIG. 1;

FIG. 4 is a bottom view of the tissue box shown in FIG. 1; FIG. 5 is a third side view of the tissue box shown in FIG. 1;

FIG. 6 is a fourth side view of the tissue box shown in FIG. 1;

FIG. 7 is a first perspective view of the tissue box shown in FIG. 1;

FIG. 8 is a second perspective view of the tissue box shown in FIG. 1;

FIG. 9 is a first side view of another embodiment of a tissue box;

FIG. 10 is a second side view of the tissue box shown in FIG. 9;

FIG. 11 is a top view of the tissue box shown in FIG. 9; FIG. 12 is a bottom view of the tissue box shown in FIG. 9; FIG. 13 is a third side view of the tissue box shown in FIG. 9;

FIG. 14 is a fourth side view of the tissue box shown in FIG. 9;

FIG. 15 is a first perspective view of the tissue box shown in FIG. 9; and,

FIG. 16 is a second perspective view of the tissue box shown in FIG. 9.
